[57] CLAIM

The ornamental design for electric space heater, as
shown and described.

DESCRIPTION

FIG. 1 is a top plan view of an electric space heater,
showing my new design;

FIG. 2 is a side elevational view, the opposite side being
a mirror image thereof;

FIG. 3 is an end elevational view, the opposite end
being a mirror image thereof; and

FIG. 4 is a bottom plan view thereof.

The conventional electrical cord has been shown fragmentarily in FIGS. 2-4 for ease of illustration.

FIG. 1

FIG. 2

FIG. 3

FIG. 4
